CAR-DOOR-OPERATING MECHANISM.

1,132,683.

Specification of Letters Patent. Patented Mar. 23, 1915.

Application filed June 10, 1914. Serial No. 344,139.

To all whom it may concern:

Be it known that I, BROR T. PETERSON, a citizen of the United States, residing at Chicago, in the county of Cook and State of Illinois, have invented certain new and useful Improvements in Car-Door-Operating Mechanisms, of which the following is a specification.

This invention relates to devices for effecting the opening and closing of freight-car doors of that type wherein the door is suspended from a trolley-rail above the door-opening, and is slid edgewise parallel with the side wall of the car in effecting the opening and closing movements of the door. It is found in practice that, under various conditions, the opening and closing of these doors is a matter of considerable difficulty. Not infrequently the contents of the car become jammed or wedged against the inner side of the door to such an extent as to make it impossible to open the latter by manually pushing the same, is is done under normal conditions. Again, in winter weather, the trolley-rail and trolleys of the door become more or less clogged with snow and ice, causing the door to stick. Still again, after a freight car has seen considerable service, the side wall of the car becomes more or less warped or the trolley-rail gets out of true position, causing the trolley-wheels to become wholly or partially derailed. These and other causes which might be mentioned often render the opening and closing of the door a matter of considerable difficulty; and the general object of the present invention is to provide a simple, inexpensive, and easily manipulated device, by the manual manipulation of which a powerful leverage can be obtained to effect the opening and closing movements of the door. By this same mechanism it is also possible to securely fasten the door in closed position, so that it cannot be opened either without a proper key or, where a key-operated lock is not employed, without destroying the usual car-seal.

My invention, its mode of use, and its advantages, will all be readily understood when considered in connection with the accompanying drawing, in which I have illustrated one practical embodiment of the invention, and in which—

Figure 1 is a fragmentary side elevation of a car, showing the car-door in closed po-

sition and with my improved operating mechanism applied thereto; Fig. 2 is a fragmentary vertical section of the car-body, door and operating mechanism as viewed from the left of Fig. 1, but with the actuating lever of the door-operating mechanism swung outwardly substantially at right angles to the plane of the door; Fig. 3 is an enlarged sectional detail on the line 3—3 of Fig. 2; and Fig. 4 is a perspective elevation of the ratchet-operating pawls, which are preferably formed in a single or integral structure.

Referring to the drawing, 5 designates the side wall of the car-body, in which is formed the usual opening 6.

7 designates the door, suspended by hanger brackets 8 and trolley-wheels 9 from a trolley-rail 10 mounted just above the door-opening; and 11 designates a series of spaced guide or keeper lugs secured to the side wall of the car-body below the door-opening and overlapping the lower edge of the door. The parts as thus far described are, or may be, all as usual in car-doors of this type.

Secured to the side wall of the car-body above and below the door-opening, as by screws 12 passing through lateral lugs 13, are a pair of upper and lower rack bars 14 and 15. Journaled in upper and lower bearings 16 and 17 on the outer face of the door 7 is a vertical shaft 18, fast on the upper and lower ends of which shaft are spur gears 19 and 20 meshing with the rack bars 14 and 15, respectively. The shaft 18 is secured in position by a pair of collars 21 and 22 keyed to the shaft above and below the upper bearing 16. Fast on a squared portion 18' of the shaft 18 are a pair of oppositely facing ratchet-disks 23 and 24 located the former directly above the latter; and straddling these ratchet disks and pivoted on the shaft 18 is the forked inner end 25' of an operating lever 25, said lever and the ratchet disks being confined on the shaft by upper and lower collars 26 and 27 keyed to the shaft. Pivoted on a vertical pin or stud 28 within the fork 25' of the operating lever are a pair of pawls 29 and 30, which are designed for co-operation with the ratchet disks 23 and 24, respectively. As most clearly shown in the detail view, Fig. 4, these pawls 29 and 30 are preferably made in a single integral structure, having 110

a common hub through which the pivot pin or stud 28 passes. On the back of this hub is formed a seat 31 for one end of a pawl-controlling spring 32, the seat-engaging end 5 of the spring being confined by a radially projecting stud 33, and the opposite end of the spring abutting against the cross member of the fork and confined by a stud 34. When the pawl 29 is in engagement with the ratchet 23, the pawl 30 is, of course, 10 in idle position relatively to its ratchet 24, and the pawls are maintained in this position by the thrust of the spring 32 against one side of the stud 33. When the pawls are shifted to the reverse position, indicated by dotted lines in Fig. 3, the spring 15 32 engages the opposite side of the stud 33, and thus acts to hold the pawls in such reversed position. Obviously, other and 20 equivalent spring pawl-controlling means might be employed.

The outer end of the operating lever 25 is preferably formed with a slot 35 which, when the door is in closed position, as 25 shown in Fig. 1, engages a staple 36 secured in the side wall of the car adjacent to one edge of the door-opening, and the operating lever may be locked to the staple 36 by an ordinary padlock or, as herein shown, by a 30 cotter pin 37, in which case the lower end of the cotter pin is preferably apertured to receive a car seal, indicated at 38.

In the operation of the mechanism, where the door may, from one or more of a variety of causes, tend to stick, the operating lever 25 is swung back and forth with the pawl 29 engaged with the ratchet disk 23. By reason of this mechanism, a very powerful leverage is obtained, tending to move 40 the door edgewise toward open position. If, when the door is to be closed, it sticks and resists an ordinary manual push, the pawls 29 and 30 are reversed to throw the pawl 30 into operative engagement with the 45 ratchet disk 24, and the operating lever 25 is similarly actuated to shift the door step by step to closed position. When the door is either closed or open, the operating lever 25 can be swung to a position parallel with 50 and closely alongside the door, where it is out of the way and not likely to be struck and injured by passing objects.

By the use of my invention, a serious practical difficulty in the manipulation of car doors of this type, which from one cause or another are more or less out of normal condition, is remedied. I am aware that it has heretofore been proposed to employ door-operating mechanisms including a vertical 60 shaft journaled on the side wall of the car and provided with one or more rack and pinion connections to the door, and with a crank or hand-wheel for turning the shaft; but such a mechanism is less efficient and 65 much harder to operate than the mechanism

herein disclosed, and in many situations could not perform the work of the latter.

I claim:

1. The combination with a car body having a side opening, and a door mounted to slide across said opening, of rack-bars secured to the outer side of the side wall of the car above and below said opening, journal bearings on the outer side of the door adjacent to the upper and lower edges 75 of the latter, a vertical shaft mounted in said bearings and carrying on its upper and lower ends spur gears meshing with said rack-bars, and shaft-operating means secured to said shaft intermediate said bearings.

2. The combination with a car body having a side opening, and a door suspended from a trolley rail above said opening and adapted to slide across the latter, of rack-bars secured to the outer side of the side wall of the car above and below said opening, journal bearings on the outer side of the door adjacent to the upper and lower edges of the latter, a vertical shaft mounted in 35 said bearings and carrying on its upper and lower ends spur gears meshing with said rack-bars, shaft-operating means secured to said shaft intermediate said bearings, and keeper lugs secured to the side wall of the 40 car body below said opening and overlapping the lower edge of the door.

3. The combination with a car body having a side opening, and a door mounted to slide across said opening, of rack-bars secured to the outer side of the side wall of the car above and below said openings, journal bearings on the outer side of the door adjacent to the upper and lower edges 100 of the latter, a vertical shaft mounted in said 105 bearings and carrying on its upper and lower ends spur gears meshing with said rack-bars, a ratchet disk fast on said shaft intermediate said bearings, and an operating lever pivoted on said shaft and carrying a 110 pawl engaging said ratchet disk.

4. The combination with a car body having a side opening, and a door mounted to slide across said opening, of rack-bars secured to the outer side of the side wall of 115 the car above and below said opening, journal bearings on the outer side of the door adjacent to the upper and lower edges of the latter, a vertical shaft mounted in said 120 bearings and carrying on its upper and lower ends spur gears meshing with said rack-bars, a pair of oppositely facing ratchet disks fast on said shaft intermediate said 125 bearings, an operating lever having a forked end pivoted to said shaft and straddling said ratchet disks, a pair of rigidly connected pawls pivoted in the forked end of said lever for co-operation with said ratchet disks respectively, and a spring operative to hold either of said pawls in engagement 130

with its ratchet disk and simultaneously hold the other pawl in idle position.

5. The combination with a car body having a side opening, and a door mounted to slide across said opening, of rack-bars secured to the outer side of the side wall of the car above and below said opening, journal bearings on the outer side of the door adjacent to the upper and lower edges of the latter, a vertical shaft mounted in said bearings and carrying on its upper and lower ends spur gears meshing with said rack-bars, a ratchet disk fast on said shaft intermediate said bearings, an operating lever pivoted on said shaft and carrying a pawl engaging said ratchet disk, and means for securing the free end of said operating lever to the side wall of the car opposite one vertical edge of said opening when the door is in closed position.
6. In a car door operating mechanism, the combination with rack-bars secured to the

outer side of the side wall of the car above and below the door opening, of a vertical shaft journaled on the door and carrying at 25 its upper and lower ends spur gears meshing with said rack-bars, a ratchet disk fast on an intermediate portion of said shaft, an operating lever pivoted on said shaft and carrying a pawl engaging said ratchet disk, 30 said lever having a slot in its outer or free end, a staple secured in the side wall of the car adjacent to one vertical edge of the door opening and adapted to be engaged by the slotted end of said lever when the door is in 35 closed position, and a cotter-pin for securing said lever on said staple, said cotter-pin being apertured for the application of a car seal thereto.
